UNITED STATES PATENT OFFICE.

ROBERT L. ALCORN, OF ONEIDA, TENNESSEE, ASSIGNOR OF ONE-HALF
TO J. T. SMITH, OF ONEIDA, TENNESSEE.

BRAKE.

No. 821,211.

Specification of Letters Patent.

Patented May 22, 1906.

Application filed June 2, 1905. Serial No. 263,460.

To all whom it may concern:

Be it known that I, ROBERT L. ALCORN, a citizen of the United States of America, residing at Oneida, in the county of Sevier and State of Tennessee, have invented new and useful Improvements in Brakes, of which the following is a specification.

This invention relates to vehicle-brakes, and is especially designed with reference to wagons, the primary object of the invention being to provide a brake the mechanism and supporting-frame of which are carried by and supported upon the hounds of the running-gear and also connected with the sand-board of one of the axles, so that all liability of the brake as a whole working loose and dropping to the ground is entirely overcome and the brake adapted to act with equal effect in either direction, or, in other words, irrespective of the direction of rotation of the wheels whether the wagon is moving forward or backward.

A further object of the invention is to provide a brake carrying and supporting frame and to so mount the brake mechanism therein and thereon that the brake as a whole may be easily and quickly applied to the running-gear of a wagon or other vehicle, so as to act with reliability and efficiency.

With the above and other objects in view, the nature of which will more fully appear as the description proceeds, the invention consists in the novel construction, combination, and arrangement of parts, as herein fully described, illustrated, and claimed.

In the accompanying drawings, Figure 1 is a bottom plan view of a portion of the running-gear of a wagon, showing the brake of this invention applied thereto. Fig. 2 is a side elevation of the same. Fig. 3 is a detail perspective view of a portion of the brake-beam, showing its connection with the brake-supporting guide-frame; and Fig. 4 is a cross-section through the guide-frame in line with the brake-beam, the latter being shown in elevation.

Like reference-numerals designate corresponding parts in all figures of the drawings.

Referring to the drawings, 1 designates the sand-board of one of the axles of a wagon, preferably the rear axle, and 2 the usual hounds. In carrying out the present invention I make use of a combined supporting and guiding frame embodying front and rear cross-bars 3 and 4, respectively, connected at

their opposite ends by longitudinally-extending parallel iron bars or straps 5, arranged one above the other at a distance apart equal to the thickness of the cross-bars 3 and 4, the opposite ends of which are bolted, riveted, or otherwise secured between the parallel bars 5, as shown. At each side of the frame one of the bars 5 is provided with an angular or flanged end portion 6, which is fastened firmly to the sand-board 1. Intermediate 65 the parallel bars are parallel braces 7, which extend lengthwise of the wagon and are secured to the top and bottom of the front and rear cross-bars 3 and 4, respectively. In this way a strong rigid frame is secured 70 which forms a guide for the brake mechanism to be described and which is connected firmly to the sand-board and which also rests directly upon the hounds 2, to which it is secured by means of bolts or rivets and clips 75 8, thereby rendering it impossible for the brake as a whole to become detached from the running-gear of the wagon and to fall downward, and thereby become partially or wholly inoperative. The construction de- 80 scribed also adapts the brake mechanism to operate upon the wheels irrespective of the direction of rotation of the same.

The brake mechanism comprises, essentially, a brake-beam 9, which extends entirely 85 across the guide-frame above described and projects at its ends beyond the sides of said frame sufficiently to receive and carry brake-shoes 10, preferably of dovetailed form in cross-section, to enable them to be detachably 90 fitted and retained in correspondingly-shaped holders 11, secured to the side of the beam adjacent to the walls, as shown. At the point where the brake-beam 9 crosses or passes between the parallel bars 5 said beam, 95 which is ordinarily of wood, is recessed in its top and bottom to receive metal runners 12, substantially U-shaped in cross-section and provided with flanges 13, which are secured firmly to the beam 9. The runners 12 em- 100 brace the parallel bars 5, and thus guide the brake-beam in its lateral movement toward and away from the wheels while also preventing undue and excessive wear.

14 and 15 represent equalizing-levers, the 105 lever 15 being coupled to the beam 9 near one end by means of a yoke or strap 16, while the lever 14 is secured in a similar manner to the opposite end portion of the beam 9 by means of another yoke or strap 17. The levers 14 110

and 15 are coupled together near the center of the guide-frame by means of another yoke or strap 18, while the lever 15 is made considerably longer than the lever 14 and extended to form an operating-arm 19. The levers 14 and 15 and the operating-arm 19 work between the parallel bars 5 and the parallel braces 7, and the arm 19 is extended laterally beyond the guide-frame sufficiently to receive pivotally one end of a connecting-rod 20, having at one end an eye 21, which fits over a headed stud or pintle 22, projecting from the extremity of the operating-arm 19. When the lever 15 and the arm 19 are formed of wood, the extremity of the arm 19 is preferably equipped with a ferrule 23 to prevent the same from splitting. The opposite end of the connecting-rod 20 is pivotally connected at 24 to the body portion 25 of a curved or bent hand-lever 26, which is fulcrumed at 27 at its lower end in a clip or bracket 28 on the outer edge of the brake-beam 9, said lever being provided with sockets or cuffs 29 to receive a suitable lever-handle, which may be inserted in or removed from said sockets. Wear or chafe irons 30 may be applied to the brake-levers where they work between the parallel bars of the guide-frame to prevent excessive wear on said levers. It is also preferred to place spacing-sleeves 31 around the bolts 32, which form the pivots between the levers 14 and 15 and the parallel bars 5, said spacing-sleeves extending up and down between the parallel bars 5 and preventing the same from being drawn together far enough to bind upon said levers, and thereby interfere with their free vibratory movements.

The brake hereinabove described is exceedingly simple in construction, reliable in operation, is adapted to work on the wheels with equal efficiency irrespective of the direction of rotation of the wheels, gives great power in operation, and will be found strong and durable in practice. Additional strength is given to the brake as a whole by reason of the fact that a suitable guide-frame is provided for the working parts of the brake mechanism, and said guide-frame is efficiently supported on the hounds and anchored to the sand-board.

Changes in the form, proportion, and minor details of construction may be resorted to without departing from the principle or sacrificing any of the advantages of the invention.

Having thus described the invention, what is claimed as new is—

1. The combination with the running-gear of a vehicle, of a frame rigidly connected to a stationary part of the running-gear and comprising upper and lower parallel bars, a brake-beam mounted to slide back and forth between said parallel bars, equalizing-levers fulcrumed between the parallel bars and pivotally coupled to each other and to the beam, one of said levers having an operating arm or extension, and a hand-operating lever connected to said operating-arm.

2. The combination with the running-gear of a vehicle, of a guide-frame fastened to a stationary part of said running-gear and comprising upper and lower parallel bars, a brake-beam mounted to slide back and forth between said parallel bars, equalizing-levers pivotally coupled to each other and to the beam and working between the parallel bars, one of said levers having an operating arm or extension, a hand-lever fulcrumed on the brake-beam, and a connection between said hand-lever and the operating-arm of the brake-lever, substantially as described.

3. The combination with the running-gear of a vehicle, of a guide-frame fastened to a stationary part of the running-gear and comprising upper and lower parallel bars, a brake-beam mounted to slide laterally back and forth between said parallel bars, runners secured to the brake-beam and embracing the parallel bars, equalizing brake-levers pivotally coupled to each other and to the brake-beam, an operating-arm forming an extension of one of said brake-levers, and a hand-lever operatively connected to said operating-arm.

4. The combination with the running-gear of a vehicle, of a guide-frame fastened to a stationary part thereof and comprising upper and lower parallel bars, certain of which are bolted to the sand-board, a brake-beam mounted to slide between said parallel bars, equalizing-levers pivotally coupled to each other and to the brake-beam, an operating-arm forming an extension of one of said brake-levers, and a hand-lever connected to said operating-arm.

In testimony whereof I affix my signature in presence of two witnesses.

ROBERT L. ALCORN.
